UNITED STATES PATENT OFFICE.

EDWARD S. COBB, OF WHITTIER, CALIFORNIA, ASSIGNOR TO COBB SHOCKLESS CROSS CORPORATION, OF NEW YORK, N. Y., A CORPORATION OF NEW YORK.

SWITCH AND FROG.

1,252,662.

Specification of Letters Patent. Patented Jan. 8, 1918.

Application filed January 11, 1917. Serial No. 141,739.

To all whom it may concern:

Be it known that I, EDWARD S. COBB, a citizen of the United States, residing at Whittier, in the county of Los Angeles, 5 State of California, have invented new and useful Improvements in Switches and Frogs, of which the following is a specification.

This invention relates to railway switches and frogs; and the invention consists in 10 certain improvements in switches and frogs as hereinafter pointed out.

Heretofore it has been common in railway switches to provide movable rails, or parts of rails, in the form of switch points movable in a horizontal plane. It is a feature 15 of my invention that the switch points are movable vertically instead of horizontally; that the switch rails are movable vertically; that the rails at the frog are movable vertically with relation to each other, so as to 20 provide free and uninterrupted and smooth passage of a wheel over the frog in either direction and on either track; and that, specifically, the whole of the switch rails, 25 between the switch points and the frog, are movable vertically bodily, each as a single, solid structure, and each in interlocking juncture with the immovable rails at the switch point and at the frog.

The fundamental feature of this invention is the vertically movable rail parts, which I will term herein "switch rails", because by their operation they switch the traffic either onto one track or onto the other. These switch rails are preferably moved vertically by a vertical reciprocating movement, so that the switch rails are always kept in horizontal position. This preferred operation enables me to form and 40 use a very solid switch rail supporting and moving mechanism and structure, to be hereinafter described. These switch rails also preferably extend from the switch points to the frog; and although this is 45 not a necessary feature of my invention, yet it is a desirable one. In my invention I wish to make a clear passage onto or off either one or the other of the two tracks, by the simultaneous raising and lowering 50 of the rails at the switch point and at the frog; and I find it advantageous to make the switch rails each in one solid structure between the switch point and the frog and to then move each switch rail as a solid unit.

55 This arrangement enables me to provide a

very strong, solid and rigid structure for supporting and moving the switch rails, and enables me to produce a switch providing a substantially continuous passage for traffic on either one track or the other, and a 60 switch which is, in all essentials, just as continuous, strong, and rigid as an unbroken integral part of a straight or curved track. In fact, it is an object of this invention to provide a switch structure over which trains 65 may proceed at unslackened speed, without jar or pounding, and to provide a switch structure whose durability and life is greatly in excess of that of any switch structure now known. Other objects of this invention are made apparent in the following 70 specification, wherein I explain a preferred form of switch structure embodying my invention.

And I refer to the accompanying drawings in which, for the purpose of this specification, I have illustrated a preferred form of structure embodying my invention. In the drawings Figure 1 is a plan of my improved switch; Fig. 2 is a horizontal plan 80 section of the same, said section being taken below the heads of the rails, and parts of the supporting box structure being broken away for purposes of illustrating the mechanism beneath; Fig. 3 is a longitudinal vertical section taken as indicated by line 3—3 on Fig. 2; Fig. 4 is an enlarged vertical cross section taken as indicated by line 4—4 in Fig. 2; Fig. 5 is a similar section taken as indicated by line 5—5 on Fig. 2; Fig. 6 85 is a similar section taken as indicated by line 6—6 on Fig. 2; Fig. 7 is an enlarged plan showing a preferred construction for the frog; Fig. 8 is a horizontal section of the same taken beneath the heads of the 90 rails; Fig. 9 is an enlarged plan showing the meeting of the rails at a switch point; Fig. 10 is a horizontal section of the same taken beneath the heads of the rails; Fig. 11 is an enlarged plan showing another 95 form of frog construction, and Fig. 12 is a similar plan showing another form of frog construction.

In the drawings I show a suitable box structure 20 which may be in any form suitable for supporting the switch structure and for housing the operating mechanism therefor. In these drawings I do not attempt to illustrate the details of construction of such a box structure, as such details will of course 100

105

110

vary with different installations. This supporting structure supports the rails 21 and 22 of the main track which leads up to the switch point, and also supports the rails 21^a, 5 22^a, 21^b and 22^b of the switch tracks which lead away from the switch point. Of course, it will be understood that one of these switch tracks may be, in reality, a main track; but it is not material to take notice of this fact, 10 so far as my invention is concerned. I illustrate the two tracks as being curved; but it will be readily seen that one of said tracks can be a straight continuation of the main track 21, 22. Therefore, without limiting 15 myself thereby, I shall refer to the two tracks 21^a, 22^a, and 21^b, 22^b, as switch tracks. The rails 21^a and 22^a may be, and preferably are, integral continuations of the rails 21 and 22; and all four rails, 21^a, 22^a, 21^b 20 and 22^b are immovably and rigidly set upon the foundation. The rail portions 21^a and 22^a, which extend from the switch points P on the rails 21 and 22, respectively, to the frogs F, are vertically movable. These 25 vertically movable switch rails 21^a and 22^a are mounted upon supporting beams 23 arranged in such relation to the movable rails as is shown in Fig. 2. Beams 23 are straight, and are not curved to follow the configurations 30 of the rails 21^a and 22^a, and are of such width as to form supports upon which all parts of the curved rails may rest. These beams are preferably constructed of a rolled steel beam 24, preferably channel shaped, 35 carrying a wooden filler 25, upon which the rails are directly supported. The rails are bolted down on the wooden filler by suitable bolts 26, which bolts also act to secure the cam bearing lugs 27 to the under sides of 40 the beams. It will be noted that the rails 21^a and 22^a rest directly upon the resilient wood filler, and are bolted thereto to prevent any upward movement, supported by the wood filler, to absorb shocks. I have 45 made this beam construction the particular subject matter of a co-pending application entitled rail support, filed March 6, 1917, Ser. No. 152,521, and I consequently do not here enter into its details.

50 The cam bearing lugs 27 are situated beneath the switch points P and frog F, and also preferably at a point or points intermediate. For instance, I show one set of cam bearing lugs 27 midway between the points 55 P and F. I locate three cam shafts 28 in suitable bearings 29; and these cam shafts carry cams 30. The shafts 28 are arranged transversely across the structure and each shaft carries two cams 30 located in such 60 relationship upon the shaft 28 that when one cam raises its cam bearing 27, the other cam lowers its cam bearing 27. I interconnect the three cam shafts 28 by suitable means, as by sprocket connections 31, so that the 65 three shafts may be operated together. The

shafts may be operated from any suitable source of power or movement, under any suitable control, and are rotated back and forth through something less than a full revolution. When the shafts are rotated to 70 one position it will be seen that one of the supporting means, with its switch rail, will be lowered while the other one is raised; and when the shafts are rotated to their other positions, it will be seen that the positions 75 of the switch rails will be reversed. It will be noted that the supporting means, including the supporting cams, etc., form very solid and rigid supports for the movable rails. Those portions of the cams which 80 are in engagement with the cam bearings when the cams are in the position shown in Fig. 3, with the rail in its uppermost position, are circular and concentric about the shaft 28; so that these portions of the cams 85 may form broad bearing surfaces for the cam bearings when the rail is in its uppermost position, and so that the rail reaches its uppermost position somewhat prior to the end of the movement of the cams, thus 90 providing that the accurate positioning of the movable rail is not dependent upon any slight variation in the amount of movement of the cam.

I have said that I prefer to make the 95 switch rails each in one solid structure, and move each of them bodily, as an integral unit between the switch points and the frog. I shall now explain how the switch rails make their junctures with the stationary 100 rails at the switch points and at the frog; and explain how the switch rails are interlocked with the stationary rails, and how they are held rigidly and firmly against any lateral displacement. At each switch point 105 I make a cut back into each of the rails 21 and 22, reaching from its inner edge transversely (substantially perpendicularly) back into the head of the rail a short distance, say a half inch or so, as illustrated at 40 (see 110 particularly Fig. 9); and then I provide a vertical bearing face 41 which leads straight from the inner end of this cut 40 to the point 42 where the outer face of the switch rail, 21^a or 22^a, meets the inner face of the rail 115 21 or 22. The switch point ends of the switch rails 21^a and 22^a are shaped correspondingly, so as to fit into the cuts and bear against the vertical faces 41, in the manner best shown in Figs. 4 and 5. The webs of 120 the rails 21^a and 22^a may be reinforced and formed to follow this vertical bearing face 41, as illustrated at 43 in Fig. 10; and the webs of these rails are further reinforced at these points, by the filler blocks 44 attached 125 to the rail webs on their inner faces. These filler blocks 44 are provided not only for the purpose of reinforcing the movable switch rails, but also are provided for the purpose of presenting bearing surfaces 45 on their 130

inner faces against which the guide members 46 may bear. These guide members 46 have outer vertical faces conformed to fit against the inner vertical faces 45 of the 5 filler blocks and are bolted, or otherwise secured, to the box structure 20, so as to form rigid guides on the inner sides of the vertically movable switch rails to prevent their displacement inwardly toward each other.

10 The webs of the rails 21 and 22 may also be enlarged or reinforced in any desired manner, as illustrated at 47, to provide the vertical bearing faces 41, as herein described, to extend below the heads of the rails 21 and 22; 15 in fact, to provide that these vertical bearing faces 41 extend vertically from top to bottom of the rails, as shown in Fig. 4. Furthermore, the webs of these rails may also be provided with reinforcements or extensions 20 in any suitable manner, as indicated at 48, to provide vertical surfaces 49 against which the suitably surfaced ends of the exterior filler blocks 50 may form bearings. These exterior filler blocks are mounted upon the 25 webs of rails 21^c and 22^c, and present outward surfaces which are guided by the outer guide members 51 secured to the box structure 20, similar to the inner guide members 46, excepting that the inner guide members 30 46 have portions 46^a providing for the passage of the flanges of wheels, while the other guide members 51 are not so provided. I thus provide against outward lateral displacement of the movable switch rails away 35 from each other; not only by the operation of the exterior guide members 51, but also by the bearings of the movable switch rails upon the surfaces 41 and 49. It will be noted that the guide members 46 and 51 extend right 40 up close to the frog F, so as to support the movable switch rails at the frog, as elsewhere. However, the frog construction is such as to lock the movable rails into place and hold them against lateral movement, as 45 will now be described.

At the frog F the two vertically movable rails 21^c and 22^c meet on a central longitudinal vertical plane 60; that is, the heads of these two rails and the inner filler blocks 44, 50 and the webs of the two rails, all meet on this central longitudinal vertical plane; being a plane of relative vertical movement. The beams 23, supporting the rails, may also be shaped and surfaced at the frog so that 55 they also meet on this same vertical longitudinal central plane 60, as is indicated in Figs. 2 and 5. The junctures of the rails 21^c and 22^c with the stationary rails 22^a and 22^b, are preferably made as shown in Figs. 60 7 and 8. I utilize vertical transverse bearing planes 61 which are located as follows: Passing through the vertical lines of meeting of the exterior head surfaces of the rails 21^c, 22^a and 22^b, 21^b, (said lines being indicated by the numeral 62 in Fig. 7) and lying

at right angles to the rails 22^a and 21^b, or lying approximately at right angles to those rails. These two planes 61, being symmetrically disposed, meet at the central longitudinal plane 60. The formation is consequently such that each of the rails 21^c and 22^c has an acute point 63, and has a vertical bearing surface 61 which extends not at right angles to the rail 21^c or 22^c, but extends diagonally back along the rail from the 75 acute point 63. Thus the bearings of the rails 21^c and 22^c at the surfaces 61 substantially and very materially prevent outward displacement of these two rails. This is due to the fact that the two rails 21^b and 22^b 80 cannot move longitudinally, because their opposite ends, at the switch points, bear against the vertical surfaces 40 as illustrated. The vertical surfaces 40 at these points may be extended by providing the 85 rails 21 and 22 with filler blocks 65, so that the vertical end bearing surfaces 40 may be extended from the top to the bottom of the rail. It will be seen that the movable switch rails are thus interlocked between the stationary rails, so that they cannot be moved either longitudinally or transversely out of proper position. At the frog F the two 90 stationary rails 22^a and 21^b may be provided with short filler blocks 66, so as to make the 95 surfaces 61 as extensive as possible, these filler blocks 66 bearing against the exterior filler blocks 50 of the movable rails. The rails 22^a and 21^b may be not only mounted securely upon the box structure, but may 100 also be secured together at the frog in any suitable manner, as by having a block 67 placed between them and securing means 68 being provided.

From the foregoing description it will be 105 seen how my switch structure is rigid and strong in construction, and how the movable switch rails are interlocked in position and cannot be horizontally displaced, either laterally or longitudinally. I will now show 110 how my switch provides a smooth and uninterrupted passage for trains over either track. Suppose, for instance, that the rail 21^c is lowered, and the rail 22^c is raised, as shown in the various views. This makes a 115 continuous passage from the track 21, 22, to the track 21^a, 22^a, the rail 21—21^a being continuous, as is hereinbefore shown, and the movable switch rail 22^c forming a continuous connection between the rails 22 and 22^a. The fact that the rail 21—21^a is not broken is readily seen from Figs. 4 and 9 of the drawings. It will be noted that the cut 120 into the head of the rail 21, as shown at 40, does not extend back to the center of the rail, and does not break the continuity of the tread surface on the head of the rail. This tread surface, or the center thereof, is indicated by the dash and dot line designated T in Fig. 9; and it will be seen that this line 130

is not broken into by the cut in the rail 21. Therefore, when the rail 21^c is lowered to afford passage for the flange over the rail 21—21^a, then there is a continuous wheel supporting surface, unbroken, on the rail 21—21^a. By further reference to Fig. 4 it will be seen that the cut back into the rail does not extend beyond the curved side portion of the upper face of the rail head, and 10 that the upper edge of bearing surface 41 is substantially in the upper or central flat part of the upper surface of the rail head. Now consider this fact in connection with the passage of a wheel over the rails 22, 22^c and 15 22^a. It will be noted that the line of tread, indicated by T' in Fig. 1, crosses this surface 41 at a very acute angle and substantially at the point where the center line of the rail 22^c meets the surface 41. The upper 20 surfaces of the rails at this point of crossing are substantially continuous, and in a substantially horizontal plane, without any dip at the point of crossing the surface 41. Consequently, there is a smooth continuous and 25 unbroken passage from the rail 22 onto the rail 22^a. At the frog F it will be noted that this tread line T' passes substantially over the center of the frog, where the rail points 63 meet. The rail 21^c being lowered, there 30 is of course a gap in the rail 22^c—22^a, at this point; but this gap only extends to the center of the rail and does not extend substantially beyond the center, so that the tread surface on the head of the rail is substantially unbroken. Furthermore, I have 35 shown, in Figs. 11 and 12, modified forms of the frog juncture; in which modified forms it will be seen that the tread line T' is not only substantially unbroken, but is perfectly 40 continuous. In Fig. 11 I show the stationary rails, 22^a and 21^b, provided with a stationary point 70, which projects centrally longitudinally between the ends of the two 45 movable switch rails 21^c and 22^c. The switch rails meet each other as before on the vertical longitudinal central surface 60, and they 50 meet this extending point 70 on the diagonal surfaces 71. The surfaces 61^a (located the same as the surfaces 61, hereinbefore 55 described) extend inwardly not to meet each other, but to meet the diagonal side surfaces 71 of the point 70.

In Fig. 12 the point 70 is shown with a rounded end 70^a, rather than an end which 55 proceeds to a sharp point, as shown in Fig. 11.

Although I have proceeded to describe this embodiment of my invention with some specific detail, I have done so in order to 60 make my invention thoroughly understood, and not because I conceive my invention to be limited to the specific features and details of construction, etc., herein described. Rather do I conceive of my invention as including many variations and modifications

which may suggest themselves in so far as they are included within the scope of the following claims.

Having described a preferred form of my invention, I claim:

1. In a railway switch, in combination with a track and a pair of switch tracks, the rails of said track extending on to form the outer rails of the switch tracks and the inner rails of the switch tracks meeting at a frog, switch rails extending between the rails of the first mentioned track, and means to vertically move the portions of the switch rails adjacent the frog and the switch points. 70
2. In a railway switch, in combination with a track and a pair of switch tracks, the rails of said track extending on to form the outer rails of the switch tracks and the inner rails of the switch tracks meeting at a frog, and vertically movable switch rails extending between the frog and switch points at the rails of the first mentioned track. 85
3. In a railway switch, in combination with a track and a pair of switch tracks, the rails of said track extending on to form the outer rails of the switch tracks and the inner rails of the switch tracks meeting at a frog, vertically movable switch rails extending between the frog and switch points at the rails of the first mentioned track, and means to move said switch rails vertically. 90
4. In a railway switch, in combination with a track and a pair of switch tracks, the rails of said track extending on to form the outer rails of the switch tracks and the inner rails of the switch tracks meeting at a frog, vertically movable switch rails extending between the frog and switch points at the rails of the first mentioned track, and means to bodily move each switch rail vertically to upper and lower positions parallel to each other. 100
5. In a railway switch, in combination with a track and a pair of switch tracks, the rails of said track extending on to form the outer rails of the switch tracks and the inner rails of the switch tracks meeting at a frog, switch rails extending between the frog and the switch points at the rails of the first mentioned track, and means to bodily move each switch rail vertically to upper and lower positions parallel to each other, said means including a supporting beam for the rail, and cam means carrying said beam and adapted to move it vertically. 110
6. In a railway switch, in combination with a track and a pair of switch tracks, the rails of said track extending on to form the outer rails of the switch tracks and the inner rails of the switch tracks meeting at a frog, vertically movable switch rails extending between the frog and switch points at the rails of the first mentioned track, and means 115

to coöperatively move said switch rails vertically.

7. In a railway switch, in combination with a track and a pair of switch tracks, the 5 rails of said track extending on to form the outer rails of the switch tracks and the inner rails of the switch tracks meeting at a frog, each of said first mentioned rails being notched on their inner faces to present a vertical shoulder in a transverse plane facing 10 toward the frog, the last mentioned rails ending at the frog at transverse surfaces, and vertically movable switch rails longitudinally confined between said shoulders and 15 surfaces.

8. In a railway switch, in combination with a track and a pair of switch tracks, the rails of said track extending on to form the outer rails of the switch tracks and the inner 20 rails of the switch tracks meeting at a frog, each of said first mentioned rails being notched on their inner faces to present a vertical shoulder in a transverse plane facing toward the frog and a vertical side bearing 25 surface extending from the rear of said shoulder diagonally along the rail at an acute angle to its longitudinal axis to the inner face of the rail, the last mentioned rails ending at the frog in transverse surfaces 30 substantially perpendicular to their longitudinal axes, and vertically movable switch rails longitudinally confined between the said shoulders and surfaces.

9. In a railway switch, in combination 35 with a track and a pair of switch tracks, the rails of said track extending on to form the outer rails of the switch tracks and the inner rails of the switch tracks meeting at a frog, each of said first mentioned rails being 40 notched on their inner faces to present a vertical shoulder in a transverse plane facing toward the frog, the last mentioned rails ending at the frog at transverse surfaces, vertically movable switch rails longitudinally 45 confined between said shoulders and surfaces, and vertical guide means at the sides of the switch rails to hold and guide them against lateral displacement.

10. In a railway switch, in combination 50 with a track and a pair of switch tracks, the rails of said track extending on to form the outer rails of the switch tracks and the inner rails of the switch tracks meeting at a frog, each of said first mentioned rails being 55 notched on their inner faces to present a vertical shoulder in a transverse plane facing toward the frog and a vertical side bearing surface extending from the rear of said shoulder diagonally along the rail at an acute angle to its longitudinal axis to the inner face of the rail, the last mentioned rails ending at the frog in transverse surfaces 60 substantially perpendicular to their longitudinal axes, and vertically movable switch rails longitudinally confined between the said shoulders and surfaces, said switch 65 rails meeting each other at the frog along a central longitudinal vertical plane, and abutting the last mentioned rails at their terminal planes, said terminal planes making acute angles with said central longitudinal meeting plane.

said shoulders and surfaces, and vertical guide means at the sides of the switch rails to hold and guide them against lateral displacement.

11. In a railway switch, in combination 70 with a track and a pair of switch tracks, the rails of said track extending on to form the outer rails of the switch tracks and the inner rails of the switch track meeting at a frog, each of said first mentioned rails being notched on their inner faces to present a vertical shoulder in a transverse plane facing toward the frog, the last mentioned rails ending at the frog at transverse surfaces, and vertically movable switch rails 75 longitudinally confined between said shoulders and surfaces, and vertical guide means on each side of each of the switch rails to hold and guide them against lateral displacement.

12. In a railway switch, in combination 80 with a track and a pair of switch tracks, the rails of said track extending on to form the outer rails of the switch tracks and the inner rails of the switch tracks meeting at 85 a frog, each of said first mentioned rails being notched on their inner faces to present a vertical shoulder in a transverse plane facing toward the frog and a vertical side bearing surface extending from the rear of 90 said shoulder diagonally along the rail at an acute angle to its longitudinal axis to the inner face of the rail, the last mentioned rails ending at the frog in transverse surfaces 95 substantially perpendicular to their longitudinal axes, and vertically movable rails longitudinally confined between the said shoulders and surfaces, and vertical guide means on each side of each of the switch rails to hold and guide them against 100 lateral displacement.

13. In a railway switch, in combination 105 with a track and a pair of switch tracks, the rails of said track extending on to form the outer rails of the switch tracks and the inner rails of the switch tracks meeting at a frog, each of said first mentioned rails being 110 notched on their inner faces to present a vertical shoulder in a transverse plane facing toward the frog and a vertical side bearing surface extending from the rear of 115 said shoulder diagonally along the rail at an acute angle to its longitudinal axis to the inner face of the rail, the last mentioned rails ending at the frog in transverse surfaces 120 substantially perpendicular to their longitudinal axes, and vertically movable switch rails longitudinally confined between the said shoulders and surfaces, said switch rails meeting each other at the frog along 125 a central longitudinal vertical plane, and abutting the last mentioned rails at their terminal planes, said terminal planes making acute angles with said central longitudinal meeting plane.

14. In a railway switch, in combination with a track and a pair of switch tracks, the rails of said track extending on to form the outer rails of the switch tracks and the inner rails of the switch tracks meeting at a frog, each of said first mentioned rails being notched on their inner faces to present a vertical shoulder in a transverse plane facing toward the frog and a vertical side bearing surface extending from the rear of said shoulder diagonally along the rail at an acute angle to its longitudinal axis to the inner face of the rail, the last mentioned rails ending at the frog in transverse surfaces substantially perpendicular to their longitudinal axes, and vertically movable switch rails longitudinally confined between the said shoulders and surfaces, said switch rails meeting each other at the frog along a central longitudinal vertical plane, and abutting the last mentioned rails at their terminal planes, said terminal planes making acute angles with said central longitudinal meeting plane, and vertical guide members on each side of each of the switch rails to hold and guide them against lateral displacement. 70
15. In a railway switch, in combination with a track and a pair of switch tracks, the rails of said track extending on to form the outer rails of the switch tracks and the inner rails of the switch tracks meeting at a frog, switch rails extending between the frog and switch points at the rails of the first mentioned track, and means to vertically move the portions of the switch rails adjacent the frog and the switch points to upper and lower positions parallel with each other. 75
16. In a railway switch, in combination with fixed track rails, vertically movable switch rails, and abutment surfaces at the opposite ends of the switch rails between which the switch rails are confined. 80
17. In a railway switch, in combination with fixed track rails, a vertically movable switch rail, and abutment surfaces at the opposite ends of the switch rail between which the switch rail is confined. 85
18. In a railway switch, in combination with fixed track rails, a vertically translatable switch rail, and vertical abutment surfaces at the opposite ends of the switch rail between which the switch rail is longitudinally confined. 90
19. In a railway switch, in combination with outer fixed track rails and inner fixed track rails which meet at a frog, a vertically movable switch rail extending between an outer rail and the frog, and vertical abutment surfaces on the fixed rail and the frog between which the switch rail is longitudinally confined. 95
20. In a railway switch, in combination with outer fixed track rails and inner fixed
- track rails meeting at a frog, a switch rail extending between an outer rail and the frog and vertically movable as a single piece. 100
21. In a railway switch, in combination with outer fixed track rails and inner fixed track rails meeting at a frog, a vertically translatable switch rail extending between an outer rail and the frog and vertically translatable as a single piece. 105
22. In a railway switch, in combination with outer fixed track rails and inner fixed track rails meeting at a frog, a switch rail extending between the frog and a switch point at an outer rail, and means to vertically move the portions of the switch rail adjacent the frog and the switch point. 110
23. In a railway switch, in combination with outer fixed track rails and inner fixed track rails, meeting at a frog, a switch rail extending between the frog and a switch point at an outer rail, abutment surfaces at the switch point and frog between which the switch rail is longitudinally confined, and means to vertically move the portions of the switch rail adjacent the frog and the switch point. 115
24. In a railway switch, in combination with outer fixed track rails and inner fixed track rails meeting at a frog, a switch rail extending between the frog and a switch point at an outer rail, and means to vertically translate the portions of the switch rail adjacent the frog and switch point. 120
25. In a railway switch, in combination with outer fixed track rails and inner fixed track rails meeting at a frog, a switch rail extending between the frog and a switch point at an outer rail, vertical transverse abutment surfaces at the switch point and frog between which the switch rail is longitudinally confined, and means to vertically translate the portions of the switch rail adjacent the frog and switch point. 125
26. In a railway switch, in combination with a fixed track rail, a vertically movable switch rail bearing laterally at its end against the fixed rail, a vertical shoulder on the fixed rail against which the end of the switch rail bears and is vertically movable. 130
27. In a railway switch, in combination with a fixed track rail, said fixed rail having a vertical lateral surface and a vertical transverse shoulder at the end of said surface, a vertically movable switch rail bearing laterally against said lateral surface with its end bearing against said transverse shoulder. 135
28. In a railway switch, in combination with a fixed rail having a vertical lateral bearing surface, a bearing block on the side of the fixed rail presenting an end surface forming a vertical transverse shoulder at the end of said lateral bearing surface; a vertically movable switch rail having lateral bearing blocks, and said switch rail and

its bearing blocks having a vertical end surface abutting said transverse shoulder.

29. A frog construction embodying, in combination with a pair of fixed rails meeting at a frog point, a pair of vertically movable switch rails adapted each to form a continuation of one of the fixed rails; said switch rails abutting said fixed rails upon vertical surfaces which are substantially at right angles to the fixed rails and at less than a right angle with the switch rails.

30. A frog construction embodying, in combination with a pair of fixed rails meeting at a frog point, a pair of vertically movable switch rails adapted each to form a con-

tinuation of one of the fixed rails, and bearing blocks mounted upon each of said fixed and switch rails; the switch rails and their bearing blocks abutting the fixed rails and their bearing blocks on vertical surfaces at substantially right angles to the fixed rails and making less than right angles with the switch rails.

In witness that I claim the foregoing I have hereunto subscribed by name this 29th day of December, 1916.

EDWARD S. COBB.
